UNITED STATES PATENT OFFICE.

GILMAN WADE, OF ST. LOUIS, MISSOURI, AND JOHN C. BURRUSS, OF CARROLLTON, ILLINOIS.

BURGLAR-ALARM.

SPECIFICATION forming part of Letters Patent No. 366,537, dated July 12, 1887.

Application filed February 7, 1887. Serial No. 226,748. (No model.)

To all whom it may concern:

Be it known that we, GILMAN WADE, of the city of St. Louis, in the State of Missouri, and JOHN C. BURRUSS, of Carrollton, in the county 5 of Greene and State of Illinois, have invented certain new and useful Improvements in Burglar-Alarms, of which the following is a full, clear, and exact description, reference being had to the accompanying drawings, forming 10 part of this specification, and in which—

Figure I shows a door and door-frame with our improvement applied. Fig. II is an enlarged view of the alarm removed from the door, and showing the bell removed and its 15 stem in section. Fig. III is an enlarged view, being a horizontal section of part of the door and through part of the alarm, showing the remainder of the alarm in top view. Fig. IV is an enlarged perspective view of the operating-lever. Fig. V illustrates a modification of 20 the lever.

Our invention relates to a burglar-alarm, to be used on doors particularly, but which may be used on money-drawers and other like 25 places, if desired; and our invention consists in features of novelty, hereinafter fully described, and pointed out in the claims.

Referring to the drawings, 1 represents the door, and 2 the door-frame.

30 3 represents the latch, having an ordinary knob, 4. The knob is secured to the spindle 5, by a screw, 6, as usual, (see Fig. V,) and secured to the spindle 5 is a lever, 7, the lever having a socket, 8, fitting over the spindle. 35 The spindle being square and the socket in the lever 7 being square, the lever is made to turn with the spindle.

40 9 represents a cord or chain secured to the outer end of the lever 7 at one end, and secured by its other end to a projection, 10, of a hammer, 11. The hammer is pivoted to a disk, 12, secured to the door by a screw, 13, the plate having a hollow stem, 14, through which the screw passes, and preferably having a lug, 45 15, that engages with the door to prevent it from turning. (See Fig. III).

The hammer 11 is pivoted to the plate 12 by a screw, 16, as shown in Fig. II, and is held cocked or is forced down by one and the same 50 C-shaped spring, 17, which has one end se-

cured to the plate 12 at 18, and bears at its other end in a socket formed in an enlargement or spur, 19, projecting from the side of the hammer. The position of the fixed end 18 of the spring 17 is such that said spring will 55 constantly exert its pressure when the hammer is in cocked position about in a line drawn through the pivotal point of the hammer, as indicated at 44 in Fig. II—that is to say, its pressure is exerted constantly toward the pivot 6c 16, by which it is sustained. The effect of this arrangement is that the spring will have a constant tendency to elevate or lower the hammer accordingly as its free extremity is on the one or the other side of the line 44. Projecting 65 from the hammer in a direction which is about radial with respect to its center of motion and at an angle of about forty degrees with respect to the spur 19, is a heel, 10, to which the chain 9 is secured. This arrangement is such that 70 when the extremity of the spring 17 is on that side of the line 44 which causes it to exert its influence to raise the hammer the extremity of the heel will impinge against the spring 17, and thereby form a stop for limiting the extent 75 to which the hammer shall be raised, as indicated in Fig. II. With the parts in the position shown in this figure it will be seen that when the hammer is moved by a pull on the chain until the socket in the extremity of the 80 spur 19 (and consequently the free extremity of the spring) is carried to the other side of the line 44, the spring will exert its pressure on the heel end of the hammer and cause its other end to be projected against the cartridge. 85

Located in line with the free end of the hammer is a holder, 29, to receive a cartridge, 20. The hammer in descending strikes this cartridge and exploding it produces a report that alarms the burglar.

90 It will be seen that by locating the spring 17 (as we have shown it) with relation to the pivot of the hammer a simple form of spring may be used, both for holding the hammer in its cocked position and for forcing it forward to 95 explode the cartridge.

The spring, hammer, and cartridge are preferably hidden from view by a bell-shaped disk, 21, secured to the outer end of the stem 14 by means of the screw 13, the object being to hide 100

the spring, cartridge, and hammer and to give to the device the appearance of an ordinary door-bell, so as to avoid disfiguring the door.

There may be used (and we prefer to use) in connection with the alarm, as described, a candle, 22, supported in a holder, 23, on a plate, 24. The plate is secured to the door near the alarm, and we have shown it secured by it being placed behind the plate 12, or between the plate 12 and the door, so that the screw 13 passes through it. In addition to this support it may be fastened by means of screws 25 at its lower end. The end of the candle is located in line with the cartridge, so that when the latter is exploded the flame will come in contact with the explosive end 26 of the candle, whereby the latter is lighted to illuminate the room at the same time the alarm is given.

20 As a modification of the lever 7, the chain or cord 9 may be secured to the shank of the door-knob by means of the screw 6, as shown in Fig. V, the chain having an extension, 9^x, which is doubled back and fastened to the main part 27. With this arrangement (as with the other) it will be seen that when the door-knob is turned in either direction the chain 9 will be pulled downward to trip the hammer.

We claim as our invention—

- 30 1. In a burglar-alarm, the combination of the cartridge-holder, the pivoted hammer, the pivot on which it is mounted, a spring exerting its pressure when the hammer is in cocked position about in a line drawn through its pivotal point, a spur projecting laterally from the hammer and upon which said spring bears, a heel projecting from the hammer at an angle to said spur, and the pull-chain connected to said heel, substantially as set forth.
- 40 2. In a burglar-alarm, the combination of the cartridge-holder, the pivoted hammer having a spur projecting therefrom in a direction radial to its pivotal point, the pivot on which the hammer is mounted, a C-shaped spring 45 having its free end in engagement with said spur, and its fixed end so located that the spring will exert its pressure when the hammer is in cocked position about in a line drawn through the pivot of the hammer, and a pull-chain connected to the hammer, substantially as set forth.
- 50 3. In a burglar-alarm, the combination of the cartridge-holder, the pivoted hammer having a spur projecting therefrom in a direction

radial with respect to its pivotal point, the pivot on which the hammer is mounted, a spring engaging said projection and exerting its pressure when the hammer is in cocked position about in a line drawn through the pivot and the fixed end of the spring, the pivot of the hammer, whereby the latter is elevated or depressed accordingly as the said spur is on one or the other side of the line in which the spring exerts its pressure, and a stop for limiting the upward movement of the hammer, substantially as set forth. 65

4. In a burglar-alarm, the combination of the cartridge-holder, the pivoted hammer having a spur projecting from the hammer radially with respect to its pivotal point, having a socket and a heel projecting from said hammer at an angle with relation to the spur, the pivot on which the hammer is mounted, a C-shaped spring having its free end in engagement with the socket in said spur, and its fixed end so situated that the spring will exert its pressure when the hammer is in cocked position about in a line drawn through toward the pivot of the hammer, the parts being so proportioned and arranged that the heel of the hammer will impinge against the spring and thereby form a stop for limiting the upward movement of the hammer, substantially as set forth. 75

5. In a burglar-alarm, the combination, with the plate 12, having the cartridge-holder and the firing mechanism secured thereto, of the hollow stem 14, the bell-shaped cap 21, placed upon said stem so as to conceal the working parts of the device, and the screw 13, passing through said cap and stem and engaging the wood-work whereby the parts are secured together, substantially as set forth. 85

6. The combination, with the cartridge-holder and the firing mechanism, of the candle 22, having the explosive end 26, situated opposite the discharge end of the cartridge, the candle-holder 23, and the plate 24, placed against the wood-work opposite the candle and cartridge for protecting said wood-work from smoke or heat, substantially as set forth. 95
